UNITED STATES PATENT OFFICE.

WILLIAM H. MEVERS, OF STURGIS, KENTUCKY, ASSIGNOR OF ONE-HALF
TO GREEN W. PRITCHETT, OF CORYDON, KENTUCKY.

PNEUMATIC COTTON-PICKER.

SPECIFICATION forming part of Letters Patent No. 659,752, dated October 16, 1900.

Application filed March 28, 1900. Serial No. 10,525. (No model.)

To all whom it may concern:

Be it known that I, WILLIAM H. MEVERS, a citizen of the United States, residing at Sturgis, in the county of Union and State of Kentucky, have invented a new and useful 5 Pneumatic Cotton-Picker, of which the following is a specification.

My invention is an improved pneumatic cotton-picker, a leading object of my invention being to provide an ambulant pneumatic apparatus which is adapted to pull the cotton downward from the bolls and avoid breaking the old hulls of the bolls, and thus prevent 10 the same from becoming commingled with 15 the cotton to the detriment of the latter.

My invention consists in the combination, with a fan-casing, of a pneumatic trunk pivotally connected thereto and a series of 20 pending flexible pneumatic tubes attached 25 to said trunk and adapted to be so disposed as to be drawn across the cotton-plants and pneumatically pick the cotton from the bolls.

My invention further consists in a flexible 25 pneumatic tube having an upturned gathering or receiving mouth adapted to pass under the cotton-bolls and subject the same to the 30 action of a downward air-exhaust current, whereby the cotton is pulled downward from the bolls without breaking the old hulls there- 35 of and causing the same to become commingled with the cotton and conveyed therewith to the receiver.

My invention further consists in the peculiar 35 construction and combination of devices hereinafter fully set forth, and pointed out in the claims.

In the accompanying drawings, Figure 1 is a 40 side elevation, partly in section, of a pneumatic cotton-picker embodying my improvements, the pneumatic trunk being shown as extended in the direction of the length of the truck or ambulant support on which the fan and operating mechanism therefor are mounted. Fig. 2 is a top plan view of the same, 45 showing the pneumatic trunk disposed in operative position at right angles to the truck and on one side thereof. Fig. 3 is a detail inverted plan view of the pneumatic trunk. Fig. 4 is a detail perspective view of one end 50 thereof. Fig. 5 is a detail sectional view of

the elbow which forms the pivotal connection of the trunk. Fig. 6 is a detail perspective view of one of the flexible pneumatic picker-tubes, showing the parts thereof disconnected. Fig. 7 is a detail sectional view of one 55 of the unions for connecting the picker-tubes to the pneumatic trunk, showing the same closed by a cap.

In the embodiment of my invention I employ an ambulatory support, such as a truck 60 or wagon of suitable construction, which is adapted to be drawn between the cotton rows, or rather astride of the same, the body 1 of said support or truck being supported by wheels 2, which are independently mounted 65 on standards or brackets 3, that depend from the body of the truck, and said wheels and said standards or brackets are of such size and proportions that the body of the truck is at such a height that the same passes over the 70 tops of the cotton-plants and clears the same. On the said truck is mounted the casing 4 of an exhaust-fan 5, and a suitable engine or motor (indicated at 6 for the purposes of illustration) is also mounted on the truck and is 75 connected to the exhaust-fan and operates the same. Any suitable form of motor and fan may be employed.

The casing 4 of the exhaust-fan is provided with a rearward-extending discharge-arm 7, 80 having the downturned elbow 8, the rear upper side of which is open, as at 9, and is covered with wire-gauze or other foraminous material, as at 10. This construction of the discharge-arm of the fan adapts the cotton which 85 is conveyed thereto to drop into a suitable basket or other receptacle below the elbow 8, while the current of air escapes through the opening 9.

The induction-opening 11 of the fan casing 90 or drum is provided with an annular flange 12, which is horizontally disposed and engages an annular groove 13 in the lower side of an elbow 14, thereby pivotally connecting said elbow to said fan-casing. To this elbow is 95 attached the inner end of a pneumatic trunk 15, the outer end of which is closed. As here shown, said trunk is rectangular in cross-section, but the same may be cylindrical in form or of any other suitable shape, and it will be 100

observed by reference to Figs. 1 and 2 of the drawings and understood from the foregoing description that the said pneumatic trunk is pivotally connected to the casing of the exhaust-fan and is adapted to be swung laterally to either side of the truck or to be disposed in any other position relative thereto. Said trunk may be of any suitable length, according to the desired capacity of the machine, so that it may be disposed, when the machine is in operation, over one or any suitable number of rows of cotton-plants. The length of the said trunk should of course correspond to the capacity of the exhaust-fan and operating-motor thereof. A rack-plate 16, which is annular in form, is disposed concentrically around the pivotal joint of the pneumatic trunk and is engaged by a detent 17, pivotally connected to the under side of the trunk, said detent and said rack-plate thus serving to lock the trunk at any required adjustment, as will be understood.

From the lower side of the pneumatic trunk depend series of flexible pneumatic picker-tubes 18, one or more of said series being provided, according to the length of the trunk and the number of rows of cotton on which the machine is adapted to simultaneously operate. The pneumatic picker-tubes of each series vary in length, as indicated in Fig. 1, and hence as the same are drawn through and across a cotton-plant, practically all of the bolls of cotton thereon are subjected to the exhaust-currents of air which pass through the picker-tubes and the pneumatic trunk. The flexible pneumatic tubes 18 are connected to the lower side of the pneumatic trunk by suitable couplings 19, each of which comprises a member 20, formed with the plate or flange 21, which is secured to the pneumatic trunk by suitable bolts or rivets, and said members 20 being coincident with openings in the lower side of the pneumatic trunk and a member 21^a secured to one of the tubes.

To the lower end of each flexible pneumatic picker-tube is coupled a metallic section 22, forming an inverted gooseneck and provided with a flared mouthpiece 23, and a globular enlargement 24 at the base of the mouthpiece.

It will be observed by reference to Figs. 1 and 6 of the drawings that the mouthpieces at the lower ends of the flexible pneumatic picker-tubes are upturned, and it will be understood that as the picker-tubes are drawn through the cotton-plants the said upturned mouthpieces pass below the bolls of cotton and subject the latter to downward exhaust-currents of air, which cause the ripe cotton to be drawn from the bolls and to be caught by and pass through said mouthpieces and picker-tubes into the pneumatic trunk, and from thence past the fan and through the discharge-arm 7 of the fan-casing, from which the cotton drops, as hereinbefore stated, into a basket or other suitable receptacle.

It is a fact that the old, dried, or rotten

hulls of cotton-bolls adhering to the plants break off very easily under stress exerted thereon in any other than a downward direction, but resist downward stress and are not so easily detached from the plants in a downward direction as in other directions. It is an object of importance to avoid detaching these old bolls and commingling them with the said cotton. By providing the flexible pneumatic picker-tubes with upturned mouths and subjecting the cotton-bolls to the action of descending currents of air, as hereinbefore stated, the cotton is abstracted from the bolls without breaking and dislodging the old, dried, or rotten hulls of the bolls, as is the case where the cotton-bolls are subjected to the action of upward currents of air applied in other than a downward direction, and hence the fragments of such hulls are not dislodged from the plants and conveyed and commingled with the cotton, and the cotton is preserved from the deterioration in quality and value incident to such commingling of the fragments of the old hulls therewith.

While the series of depending pneumatic picker-tubes will as they are drawn across the cotton-plants pick or abstract the major portion of the cotton from the bolls, some of the bolls will of course escape the action of said pneumatic picker-tubes and will be left intact upon the plants. Hence in order to thoroughly harvest the cotton crop the same must be gleaned by hand, and to adapt my improved pneumatic cotton-picking machine to be used for the purposes of such gleaning simultaneously with its efficient operation in picking the major portion of the cotton I provide the pneumatic trunk with a suitable number of flexible pneumatic tubes 25, which are of sufficient length to be grasped and manually operated by persons who walk between the rows of cotton plants in rear of the machine. Said tubes 25 are similar to the tubes 18, excepting in length.

Having thus described my invention, I claim—

1. In a cotton-picking machine, a fan-casing, a pneumatic trunk pivotally connected thereto and flexible pneumatic picker-tubes attached to said trunk, substantially as described.

2. In a cotton-picking machine, the combination with a fan-casing, a pneumatic trunk pivotally connected thereto, means to secure said trunk at any desired adjustment, and flexible pneumatic picker-tubes attached to said trunk, substantially as described.

3. In a pneumatic cotton-picker, a flexible pneumatic picking and conveying tube having an upturned mouthpiece, and means to create an exhaust-air current through said tube, the said mouthpiece being the intake of said exhaust-air current, substantially as described.

4. In a pneumatic cotton-picker, a flexible pneumatic picking and conveying tube hav-

ing an upturned mouthpiece, said mouth-piece being flared upwardly, and means to create an exhaust-air current through said tube, the said mouthpiece being the intake of said exhaust-air current, substantially as described.

5. In a pneumatic cotton-picker, a pneumatic trunk, flexible pneumatic picker-tubes communicating therewith and depending therefrom, said picker-tubes having upturned mouthpieces at their lower ends forming air-intakes and means to create exhaust-air currents through said flexible depending picker-tubes and said pneumatic trunk, substantially as described.

10. In a pneumatic cotton-picker, the combination with a fan-casing and an exhaust-fan therein, of a pneumatic trunk communi-

cating with said casing, said trunk being pivotally supported and adapted to be swung to any desired angle to either side of the machine, and a series of flexible pneumatic picker-tubes attached to and depending from the said trunk, the said depending, flexible picker-tubes having the upturned mouthpieces at their lower ends forming air-intakes for the exhaust-air currents created by the fan, for the purpose set forth, substantially as described.

15. In testimony that I claim the foregoing as my own I have hereto affixed my signature in the presence of two witnesses.

WM. H. MEVERS.
